(57) **CLAIM**

The design for door mounting shim, as shown and described.

DESCRIPTION

FIG. 1 is a front perspective view of the door mounting shim in a retracted configuration;

FIG. 2 is a rear perspective view of the door mounting shim in the retracted configuration;

FIG. 3 is a rear view of the door mounting shim in the retracted configuration;

FIG. 4 is a front view of the door mounting shim in the retracted configuration;

FIG. 5 is a left side view of the door mounting shim in the retracted configuration;

FIG. 6 is a right view of the door mounting shim in the retracted configuration;

FIG. 7 is a top side view of the door mounting shim in the retracted configuration;

FIG. 8 is a bottom side view of the door mounting shim in the retracted configuration;

FIG. 9 is a front perspective view of the door mounting shim in an extended configuration;

FIG. 10 is a bottom sectional view taken along 10-10 of FIG. 9 of the door mounting shim in the extended configuration; and,

FIG. 11 is a section view along 11-11 of FIG. 10.
